UNITED STATES PATENT OFFICE.

JAMES PAPPA, OF OSWEGO, NEW YORK.

FIRE-ESCAPE.

SPECIFICATION forming part of Letters Patent No. 275,514, dated April 10, 1883.

Application filed February 15, 1883. (No model.)

To all whom it may concern:

Be it known that I, JAMES PAPPA, a naturalized citizen of the United States, residing at Oswego, in the county of Oswego and State of New York, have invented certain new and useful Improvements in Fire-Escapes; and I do hereby declare the following to be a full, clear, and exact description of the invention, such as will enable others skilled in the art to 50 which it appertains to make and use the same, reference being had to the accompanying drawings, and to letters or figures of reference marked thereon, which form a part of this specification.

15 This invention relates to apparatus for facilitating the escape of persons from burning buildings; and it consists in the construction and combination of devices hereinafter particularly set forth and claimed.

20 In the accompanying drawings, Figure 1 represents a perspective view of a building provided with my improved fire-escape apparatus. Fig. 2 represents a detail view of one of the traveling pulley-blocks for suspending the ladders and baskets. Fig. 3 represents a detail view of one of the folding baskets. Fig. 4 represents a detail view of one of the flexible ladders. Fig. 5 represents a detail view of a supplemental ladder for allowing escape from 25 the roof. Fig. 6 represents a vertical sectional detail view of one of the blocks and its pulleys and certain devices for preventing the rotation of the lower pulley when the descending basket draws the chain over the latter, 30 said view being taken from the side next the building; and Fig. 7 represents in detail the spring-hook which holds the endless chain together, the nearer of said chain being shown also.

35 A designates the building to which the fire-escape apparatus is applied; B, an iron track, rigidly suspended by hooks *b* from the cornice *a*; and C, a horizontal rod, supported rigidly on top of said cornice by brackets *c*. Both the 40 track below and the guide-rod above are carried around the corners of the building without sharp angles. This construction of the track B allows the fire-escape ladders and baskets to be shifted from one side or face of 45 the building to another, as needed.

50 D designates a series of blocks or frames,

each of which is open at the middle to allow it to be set upon said track, and provided in its upper part with a pulley, *d*, which rests on said track. The lower end of each block or frame D is provided with a hook, *d'*, and at least one of them has, in addition, a pulley, *d''*, near its lower end. This lower pulley, *d''*, receives an endless chain, (marked E,) to which a basket, F, is detachably secured on one side 55 by means of a spring-hook, *f*, which also serves to allow the chain itself to be opened and removed from its block when desired. This basket consists of an open-work bottom, F', a rim, F'', bail F''', and oblique curved side links, F''. Eyes *f'* are formed on the said bottom, and corresponding eyes, *f''*, are formed on said rim, the side links, F'', being loosely connected to said eyes *f'* and *f''*, so that they will turn and allow the basket to be folded or flattened, as 60 shown in Fig. 3. The spring-hook *f* catches over the bail F''', and the chain E passes through the bottom of the basket to guide it in an upright position. When a person desiring to escape steps into it, he grasps the opposite side of the chain and lets himself gradually down, his own weight furnishing the motive power. The pressure of his weight on the bottom F' and the draft through his hands and chain E upon bail F''' operate to keep said 65 basket distended. The chain E should be long enough to reach the ground, or at least to be grasped by a person standing on the ground, so that the said chain may be pulled to raise or lower said basket, and to move it 70 laterally to the point where it is needed. When out of use said basket may be folded or flattened, as before described, and hung on hook *d'*. Of course these baskets may be as numerous as desired, though only one is shown. 75 They should be made of some incombustible material, preferably wrought-metal rods, round or flat, or strong wire.

G designates a rigid ladder, and H a flexible ladder, which are hung, respectively, to hooks *d'* of other blocks D. These ladders should be of such length that they may be reached from the ground and moved laterally to the point where needed.

I designates a supplemental ladder, provided 80 on its back with hooks *i*, which may be caught over horizontal rod C. This ladder allows par-

ties on the roof to escape therefrom to one of the baskets or lower ladders suspended from the track below. Under ordinary circumstances all the ladders and baskets supported by said track are assembled at the least conspicuous point at the back of the building. On the alarm of fire they are grasped from below and hurried to the threatened point. There is no need for any one to ascend to the roof or enter the building, except for the purpose of disengaging the baskets from the hooks d' . Even this may be made unnecessary by shortening each spring-hook f' , so that it will not prevent the chain E from being pulled through the block D sufficiently to lift bail F^3 in each instance off from hook d' .

Instead of hanging the flexible ladders on hooks d' , they may be hung on the lower parts of the blocks or frames D . Any one of the lower rounds may then be caught upon the hook d' , in each instance, to shorten the ladder or retain it folded out of the way.

The lower pulley, d^2 , over which passes the endless chain E , preferably has attached to it a ratchet-wheel, O , which is adapted and arranged to engage with a spring-pressed dog, P , attached to the block D , thereby locking said pulley d^2 against rotation when the basket F descends. Said chain then merely draws over said pulley, and its friction thereon lessens the rapidity of its descent. When the basket is ascending, the chain moves more easily, because the dog then allows the ratchet-wheel to turn freely under it, and of course there is no impediment to the rotation of the pulley d^2 , except the friction of said dog on the inclined faces of the ratchet-teeth.

I am aware that it is not broadly new to provide a building with a track running around the same at or under the roof, and with pulleys which are supported on said track and move thereon, endless chains being passed over said pulleys, and having devices for facilitating escape—such as buckets or chains—attached to them. I therefore do not claim, broadly, the said construction and combination of fire-escape apparatus; but,

Having thus described my invention, what I claim as new, and desire to secure by Letters Patent, is—

1. The track B , extending around a building below the roof, without sharp angles at the corners, in combination with fire-escape devices arranged to travel thereon, a horizontal rod, C , supported at or above the edge of the roof, and a supplemental ladder, I , provided with hooks i , whereby it may be attached to said rod C to allow parties on the roof to reach said lower fire-escape devices, substantially as set forth. 50

2. In combination with track B and block D , having pulleys d d^2 and hook d' , an endless chain passing over the lower pulley, and a basket which is attached to said chain, for the purpose set forth. 55

3. A block, D , having pulleys d d^2 and track B , on which pulley d runs, in combination with chain E , provided with a spring hook or catch which detachably secures the ends of the chain together and the bail of the basket to said chain, substantially as set forth. 60

4. A metallic basket consisting of open-work bottom F' , having eyes f' , rim F^2 , having eyes f^2 , bail F^3 , and folding side links, f^3 , in combination with chain E , block D , and track B , substantially as set forth. 70

5. In a fire-escape, the combination of pulley d^2 and the endless chain passing over the same, with the ratchet-wheel O , turning with said pulley, and the dog P , engaging with said ratchet, for the purpose of preventing the rotation of said pulley when the basket attached to said chain is descending, but allowing the rotation of said pulley when said basket rises, substantially as set forth. 80

In testimony whereof I affix my signature in presence of two witnesses.

JAMES PAPPA.
